UNITED STATES PATENT OFFICE.

GEORGE LEWIS PRATT, OF ATLANTA, GEORGIA.

PULVERIZING-MILL.

No. 826,061.

Specification of Letters Patent.

Patented July 17, 1906.

Application filed August 14, 1905. Serial No. 274,210.

To all whom it may concern:

Be it known that I, GEORGE LEWIS PRATT, a citizen of the United States, residing at Atlanta, in the county of Fulton and State of Georgia, have invented certain new and useful Improvements in Pulverizing-Mills; and I do hereby declare the following to be a full, clear, and exact description of the invention, such as will enable others skilled in the art to

10 to which it appertains to make and use the same.

Much difficulty has been experienced in the past in securing from a centrifugal pulverizing-mill a product of sufficient fineness without the use of separating-screens surrounding 15 the pulverizing-chamber of such fine mesh, and consequently so fragile, as to result in serious damage and wear and tear from the flying lumps or particles of the material delivered to the interior of the pulverizing-chamber.

20 Among the more important objects, therefore, of my invention are, first, the peculiar arrangement of a fine or final separating-screen relative to an inner heavier or coarser protecting-screen and the inclination of both fine and coarse screens from the vertical line, whereby in operation the material passing the inner protecting-screen must necessarily fall upon the outer or finishing screen, there- 25

30 by giving a gravity separation which must necessarily result in the passage of all or at least the major part of the sufficiently fine material through the outer or finishing screen without serious wear and tear which neces-

35 sarily occur if the inner or protecting screen were not used; second, the peculiar formation or arrangement of a pulverizing-ring with relation to a pulverizing-roller and with reference to the screens surrounding the pul- 40

verizing-chamber, whereby the "splash" resulting from the contact of the pulverizing-roller with the material lying along the inner surface of the pulverizing-ring will be practically parallel to the screens, thereby assisting 45

to produce a gravity separation which could not otherwise be obtained; third, the peculiar arrangement of the revolving table carrying the roll-shafts and forming the upper housing of the pulverizing-chamber and the 50

55 provision of strengthening-ribs placed underneath which table for subserving the dual function of supports and of creating a blast-wheel effect, forcing a current of air against the screen which assists in the separation and

the cleaning of the screens, openings at or near the center of the revolving table allow-

ing the introduction of the material to be pulverized, said openings also permitting the ingress of air occasioned by the said blast effect; fourth, the provision of an additional housing above the top of the revolving table with openings at or near its center, so that any leakage or escape of dust from the pulverizing-chamber will be drawn back through the openings in the top of the revolving table.

With these objects in view and others the invention consists in the novel construction, combination, and arrangement of parts, as will be hereinafter fully described in the specification, illustrated in the drawings, and 70 summed up in the claims.

In the accompanying drawings, Figure 1 is a vertical section through my improved pulverizing-machine. Fig. 2 is a horizontal section on line 1 1, and Fig. 3 is a horizontal section on line 2 2.

Referring to the drawings, the bed-plate or base A of the machine may be made of any desired shape, preferably circular, and is formed with a curved conical annular flange 80 a^2 , connected with an outer curved annular flange a^3 by radial ribs a^4 , which flange a^2 , with the bottom a^5 , constitutes the pulverizing pan or receptacle for the incoming material. On the inner face of the pan a^2 may be secured a 85 conical pulverizing-ring B. Secured around an annular notch a^6 in flange a^3 is an annular drum or casing a^7 . Legs or standards C are secured to base A and extend upward for a distance and then converge and are bolted to 90 a head D. Bolted to the standards C is a spider E, which carries at its center the main bearing F, which bearing carries the main vertical shaft G. Preferably bolted between the ribs or spokes of spider E are segmental 95 covers e^2 , which are provided with annular downward-projecting curved flanges e^3 , provided with annular notches to carry the annular casing a^7 , an outer screen a^8 , and an inner screen a^9 . The lower edge of the outer 100 screen a^8 is desirably carried by a conical flange a^{10} , preferably forming part of the pulverizing member B, but in the drawings shown as separate and clamped thereto. The lower edge of the inside screen a^9 is desirably 105 carried by lugs or straps a^{11} , fixed at intervals to the flange a^{10} . These lugs are sufficiently separated from each other around the flange a^{10} to hold securely in position the bottom of the inner coarse screen a^9 and at the same 110 time not to prevent the passage of material which has passed through screen a^9 and has

been rejected by screen a^8 back into the pulverizing-pan—that is, not to prevent it from falling out at the bottom between the two screens a^8 and a^9 over the edge of the pulverizing member B into the pan.

5 The main shaft G may be supported at its head g^2 by various bearing-disks g^3 , g^4 , and g^5 on the flanged bearing-lining g^6 and is driven by gears H and H' and pulley H².

10 At the lower end of shaft G is carried the revolving table J, which is provided on its under side with ribs J' for the support of the trunnion-blocks K. The table is finished at its outside edge so that it will rotate very 15 nearly adjacent to the segments e^2 , as shown at j^2 . Near the center of revolving table J and immediately outside the hub are provided openings j^3 and the segments e^2 not reaching entirely to the center of the spider E. Openings e^5 are formed through any or all 20 of which and through the openings j^3 feed may be delivered to the machine and also through which comes in air drawn in by the fan action of the ribs J' under table J. Carried by ribs J' and revolvably secured therebetween are trunnion-heads K, into which are secured shafts K', carrying revoluble rollers K².

25 The material to be pulverized is fed into the machine through any suitable hopper, (not shown,) falls downward into the pulverizing-chamber, is caught by the rollers K² or the plows k³, and brought out into contact with the pulverizing-ring B, where it is crushed or pulverized by the rolling action of the rollers K² on ring B. Any material more 30 or less finely pulverized is splashed up onto the surface of screen a^9 , as is also other material thrown thereon by the action of all the inner revolving parts. Any of such material, 35 whether splashed from the ring or thrown by the revolving parts, which is of sufficient fineness passes through the coarse screen a^9 and falls upon outer screen a^8 , where a further separation takes place of any degree of fineness desired, determined only by the fineness 40 of mesh of screen a^8 . Any material rejected by screen a^9 immediately falls back to be again caught between the surface of the rollers K² and the inner surface of ring B for 45 further pulverization. Similarly material which has passed through screen a^9 , but has been rejected by screen a^8 , falls between the two screens and in over the edge of the pulverizing-ring B to be similarly further pulverized. Material of sufficient fineness having 50 passed through both screens a^8 and a^9 is prevented from escaping by the cylindrical casing a⁷ and falls therefrom down through the spaces a¹², formed by the ribs a⁴, into a 55 suitable hopper or conveyer underneath the machine. Similarly air drawn into the machine by the fan action of the revolving parts passes through the screens and down through the same channels a¹², from whence it can be 60 delivered in any direction desired.

It will be noticed that a small crack (shown at j^2) must necessarily exist between revolving table J and the downward-projecting flanges e^3 of the segments e^2 . Also there must be some crack around the trunnion-heads K 70 where they fit into and are attached between the ribs J' of revolving table J. (See Figs. 1 and 2.) If, therefore, no additional housing such as is formed by these segments e^2 were provided above the top of the revolving table, 75 escape of dust through the cracks mentioned must necessarily be free to the outside air, and similarly would this be the case if there were any openings in this housing other than those e^5 , (shown at or about the center of the 80 segmental covers e^2 .) The housing e^2 above the top of the horizontal table J therefore subserves the very important function of collecting and reintroducing at the center any flying particles escaping from around the outside edge of the revolving table. The peculiar construction of the parts permits of absolute closing of the pulverizing-chamber except at or near the center, through which there must necessarily be a suck of air rather 85 than an outblow. It will further be noticed that a distinct advantage is gained by placing the lower or driving pinion H' below the main gear H, this advantage being twofold—first, the gear is between the bearings, and, 90 second, the belt leading away from pulley H², the lower side of which is preferably the pulling side, brings all of the wear on the horizontal bearing in this shaft in one direction, and the inner bearing of this horizontal 95 shaft acting as the fulcrum and the upper gear H as the work, similarly the strain on this inner bearing must necessarily be in the same direction as that on the outer bearing. Therefore the alinement is always perfectly 100 maintained.

Having thus fully described my invention, what I claim as new, and desire to secure by Letters Patent, is—

1. In a pulverizing-machine, a practically-110 inclosed pulverizing-chamber formed at the bottom by a pulverizing-pan, at the sides by a surrounding drum or casing, and at the top by a housing open only at the center; a revolving table supported beneath the housing 115 and carrying roller-supporting shafts, said table being provided with openings at the center; and an outside and an inner screening-surface disposed about the pulverizing-pan, and against which there is a fan action 120 induced by the roller-shafts, when the machine is in operation.

2. In a pulverizing-machine, a practically-125 inclosed pulverizing-chamber formed at the bottom by a pulverizing-pan, at the sides by a surrounding drum or casing, and at the top by a housing open only at the center; a revolving table supported beneath the housing and carrying roller-supporting shafts and having strengthening-ribs underneath, said 130

table also being provided with openings at the center; and an outside and an inner screening-surface disposed about the pulverizing-pan and against which there is a fan action induced by the ribs and roller-shafts, when the machine is in operation.

3. In a pulverizing-machine, a practically-
inclosed pulverizing-chamber formed at the
bottom by a pulverizing-pan, at the sides by
10 a surrounding drum or casing, and at the top
by a housing open only at the center; a re-
volving table supported beneath the housing
and carrying roller-supporting shafts and
having strengthening-ribs underneath, said
15 table also being provided with openings at
the center; and an outside and an inner
screening-surface disposed about the pulver-
izing-pan and in close proximity one to the
other, and against which there is a fan action
20 induced by the ribs and roller-shafts, when the
machine is in operation.

4. In a pulverizing-machine, a practically-
inclosed pulverizing-chamber formed at the
bottom by a pulverizing-pan, at the sides by
25 a surrounding drum or casing, and at the top
by a housing open only at the center; a re-
volving table supported beneath the housing
and carrying roller-supporting shafts and
having strengthening-ribs underneath, said
30 table also being provided with openings at
the center, and an outside, and an inside,
heavier and coarser screening-surface dis-
posed about the pulverizing-pan and in close
proximity one to the other, and against which
35 there is a fan action induced by the ribs and
roller-shafts, when the machine is in opera-
tion.

5. In a pulverizing-machine, a practically-

inclosed pulverizing-chamber formed at the
bottom by a pulverizing-pan, at the sides by 40
a surrounding drum or casing, and at the top
by a housing open only at the center; a re-
volving table supported beneath the housing
and carrying roller-supporting shafts and
having strengthening-ribs underneath, said 45
table also being provided with openings at
the center, and an outside and an inner
screening-surface slantingly disposed about
the pulverizing-pan and in close proximity
one to the other, whereby there is a gravity 50
separation of material thrown thereagainst,
and against which there is a fan action in-
duced by the ribs and roller-shafts, when the
machine is in operation.

6. In a pulverizing-machine, a practically- 55
inclosed pulverizing-chamber formed at the
bottom by a pulverizing-pan, at the sides by
a surrounding drum or casing, and at the top
by a housing open only at the center; a re-
volving table supported beneath the housing 60
and carrying roller-supporting shafts and
having strengthening-ribs underneath, said
table also being provided with openings at
the center, and an outside and an inner
screening-surface slantingly disposed about 65
the pulverizing-pan and in close proximity
one to the other; said pulverizing-pan being
formed with a grinding-surface having a sub-
stantially parallel inclination to the slant or
incline of the screening-surfaces. 70
